APPARATUS FOR OPERATION OF GAS-FILLED MULTICATHODE CHARACTER DISPLAY DEVICE

Donald Leroy Klipstein, Chicago, Ill., assignor to Illinois Testing Laboratories, Inc., Chicago, Ill., a corporation of Illinois

Filed Feb. 1, 1960, Ser. No. 6,054

10 Claims. (Cl. 315—135)

This invention relates generally to system or apparatus for use with gas-filled multi-cathode tubes and more particularly is concerned with a novel circuit or apparatus for use in the operation of such tubes.

In recent years, the read-out of data from many electronic apparatuses has been achieved in the form of pulses or signals which are capable of driving some form of indicating device to give a visual display. For example, gaseous discharge tubes have been devised which have a plurality of cathodes and one anode, the different sources of signal being connected to be applied to the respective cathodes to cause the cathode to glow as a manifestation of flow of current from that particular cathode to the anode. Such display devices are of several types, including those which have the cathode arranged in a configuration of a character, such as the characters 0 to 9 all arranged in parallel planes but aligned front to rear so that the viewer can only see the particular cathode which glows, and including those in which the cathodes are arranged in a circle and comprise short lines or points cooperating with a circular scale provided externally of the tube.

The structure of such tubes is characterized by the provision of a glass envelope having one surface through which the characters are visible, containing the electrodes and an ionizable gas such as neon along with other inert gases, for example small amounts of krypton, argon, etc. The tube is inoperative unless the gas is ionized, and this requires an ionizing potential between a cathode and anode which exceeds that which is characteristic of the gas or mixture of gases. The potential is applied between the anode and that cathode which it is desired to display, the ionization of the gas causing a visible glow in the vicinity of the cathode which has been energized, the cathode necessarily being at a negative potential.

The manner of connecting such display devices into circuits has in the past involved the simple connection of the different input circuits to the respective cathodes and affording a common return from the anode, but such circuitry assumes sufficient power to drive the cathodes. Where very low power is all that is available some form of amplification is required, but this assumes expensive proportions since most of the character display lamps have at least ten cathodes, so that the cost of a single amplifier is multiplied ten-fold. Another problem which heretofore has not been solved economically has been the isolation of cathodes one from the other to prevent more than one cathode from becoming energized when a signal is applied thereto.

The primary object of the invention herein is to overcome the disadvantages which are alluded to above, and to provide apparatus for operating a multi-cathode character display device which utilizes extremely low power, which is simple in construction and operation, which is economical to manufacture and maintain, and which requires a very small number of small and readily obtained components.

Other objects and advantages will appear to those skilled in this art as the preferred form of the invention is explained in connection with a circuit diagram in which conventional symbols are used to designate the several parts. Obviously, modifications and changes can be made

2

without departing from the spirit or scope of the invention.

In the circuit diagram, the gas-filled multi-cathode character display tube is designated V₁ and it has the cathodes C-1, C-2, C-3 etc. through C-10 each of which may be in the form of some display character, such as shown herein, comprising the characters 0, 1, 2 etc. through 9. The anode is designated A and symbolically extends the entire length of the tube V-1 to be available to collect the electrons flowing from cathodes. When a discharge occurs between any cathode and the anode, the cathode will glow and display the character in which configuration the cathode has been formed.

The anode A is connected by way of the lead 22 to the anode supply B through a suitable limiting or ballasting resistor R-11 and the return conductor for the transistors is 24 which includes a high ohmage resistor R-12. The return conductor 24 comprises the common input lead for all of the control inputs which are shown at the bottom of the diagram and places a positive voltage on the emitters. The inputs in the diagram are numbered in accordance with the respective characters which it is desired to display, and represent a source of input signal, which if energized will cause the particular cathode with 25 which it is connected to glow.

The negative terminal of the anode supply is connected by way of the lead 26 to each of the collectors of ten transistors designated Tr-1 through Tr-10 which provide the necessary amplification and switching needed to operate each of the cathodes.

Each transistor is connected in the emitter follower configuration, with the input in effect applied between its emitter and base. The resistors R-1 through R-10 comprise the biasing resistors and are chosen so that a small 35 signal will be sufficient to cause the respective transistors to conduct between emitter and collector. Thus, for example, if a signal of say one volt is applied between the input marked 4 and the common lead 24, the normally non-conducting transistor Tr-5 will conduct because of the flow of current from the emitter to the collector. The signal cannot affect any of the other transistors because of the diodes D-1 to D-10. As for the signal between lead 24 and the input 4, current may flow from 4 through the diode D-5 but the polarity of the other diodes relative to D-5 prevents any of the transistors but Tr-5 from receiving a signal.

Once conduction is established through transistor Tr-5, current may flow through the lead 28, the diode D-15 and from the cathode C-5 to the anode A. With the 50 circuit completed as described, all of the voltage of B appears between the cathode C-5 and the anode A (but for a small drop in the transistor Tr-5 which is of no consequence). This enables the discharge to occur between cathode C-5 and the anode A, which causes current to flow in the circuit described. Current will not flow through any of the diodes but D-15 because of the polarity and hence, the energization of one cathode such as C-5 will not affect the others. The flow of current is limited only by the resistor R-11 and will continue 55 only so long as the signal is applied to the input of transistor Tr-5 and that transistor is conducting.

In effect, the transistors Tr-1 through Tr-10 are semiconductor switching devices in emitter-follower configuration which are actuated by the signals which are applied to their respective bases. The voltage which is controlled by the transistors is that of the B supply which may be of the order of 150 volts, supplied either by a battery supply or by any suitable alternating current 65 energized rectifier circuit. In a practical circuit, the multi-cathode character display lamp comprises a lamp designated NUP-102, having actual number configuration 70

tions for cathodes. The physical characteristics of the circuit were as follows:

Transistors Tr-1 through Tr-10	2N398 (p-n-p)
Diodes D-1 through D-20	1N191
R-1 through R-10 (each)	3300 ohms
R-11	15,000 ohms
R-12	150,000 ohms

Through the apparatus which has been described above, it is possible to energize the desired cathode of the display tube V-1 with a signal as low as one volt in amplitude. In order to prevent the transistors from being overloaded and burned out, the input signal for the apparatus should be within the rated limits of the transistor, this being a maximum of three volts for the practical circuit described.

The circuit as described is applicable to any of the multi-cathode gas-filled character display lamps which are available at the present time, and in view of the small space occupied and the economy of components, as well as the ability of the circuit to operate with extremely low voltages, the display lamp is thus rendered more flexible and utilitarian for read-outs whose signals are normally considered of insufficient amplitude and power to drive such a device.

The circuit which has been described has been successfully utilized, but can be varied as to its circuit constants and in other minor details. The list of components above shows that the transistors Tr-1 to Tr-10 are all of the p-n-p type, this being a great advantage because the present cost of such transistors is many times less than the cost of n-p-n type transistors. The circuit herein is also not obvious in view of the polarity requirements of the multi-cathode display devices and the inherent polarity characteristics of p-n-p transistors.

Some conception of the size of the apparatus can be obtained by considering that the entire structure, exclusive of the tube V-1 and the power supply B, but including a mounting wafer and all connections occupied a space 1½ inches wide, 3½ inches long and $\frac{1}{10}$ inch thick.

What it is desired to secure by Letters Patent of the United States is:

1. Apparatus for operating a gas filled multi-cathode display device from a plurality of signal inputs of relatively low power, said device having a plurality of cathodes and an anode and the inputs adapted to be connected to energize desired ones of said cathodes, comprising a potential source having one terminal thereof connected to said anode, a semi-conductor switching device comprising a p-n-p transistor connected between each cathode and the second terminal of the said potential source, and each switching device having an input circuit and the inputs adapted to be connected to the respective input circuits, means for biasing each transistor to conduct only when there is a signal applied to its respective input, and means for isolating each cathode from one another to prevent any one signal from energizing other than the cathode connected to the transistor in the circuit to which said signal has been applied.

2. Apparatus as claimed in claim 1 in which the means for isolating the cathodes comprises at least one unilateral conducting device in series connection between each of said cathodes and its associated transistor, the unilateral conducting devices all being polarized in the same direction.

3. Apparatus as claimed in claim 2 in which at least an additional unilateral conducting device is connected in series with each of said input circuits whereby to prevent the application of a signal to one circuit from affecting any of the others, all of said additional unilateral conducting devices being polarized in the same direction.

4. Apparatus for operating a glow lamp discharge device having a plurality of cathodes and an anode, which comprises a plurality of transistor circuits, each having a

p-n-p transistor including a base, emitter and collector, a source of potential, a continuous connection from said anode through said source of potential and through the emitters and collectors of each transistor to the respective cathodes whereby each cathode forms one of said transistor circuits with one transistor, each transistor circuit normally being non-conducting whereby the connection including the cathode and anode of that circuit is open, an input circuit for each transistor including a connection across the base and emitter of the respective transistors adapted to have an input signal applied thereto, there being first biasing means across each base and emitter, second biasing means for the emitters of each transistor, and said second biasing means being connected in said continuous connection, the transistors each serving as a switching device and being rendered normally non-conductive by said biasing means but being rendered conductive by means of a signal applied to the input of any one transistor circuit, whereby the cathode

10 of that transistor circuit will glow.

5. Apparatus as claimed in claim 4 in which there is an isolating diode in series with the connection between each cathode and its respective transistor circuit to prevent any but one cathode to be activated by a single signal.

6. A glow-discharge circuit comprising, a multi-cathode tube having a plurality of cathodes and an anode, and each cathode adapted to be rendered glowing by the application of a signal thereto from a plurality of respective signal sources, a source of direct current potential having its positive terminal connected to said anode, a plurality of p-n-p transistors each having at least a base, an emitter and a collector, each cathode being connected to the negative terminal of said potential source 30 through the emitter and collector of one of the respective transistors, the signal sources each being connected respectively to the base of a transistor and to one of its other electrodes, a biasing connection from said potential source to all of the transistors, and a biasing resistor connected between each base and emitter circuit for rendering the respective transistor non-conducting unless a signal is applied thereto.

7. A circuit as claimed in claim 6, in which each cathode connection has an isolating diode therein, and each transistor has a second isolating diode in its input, and means are provided for ballasting the tube when discharge occurs.

8. In an apparatus for operating a gas filled multi-cathode display device from a D.C. source, a plurality of switching circuits, one connected to each respective cathode of said display device, each circuit including a p-n-p transistor connected in emitter-follower configuration, means for connecting a signal input to the base and emitter of said transistor, means for biasing said transistors from said source, and means for isolating the switching circuits one from the other.

9. In an apparatus for operating a gas-filled multi-cathode character display device from a D.C. source connected between the anode of said device and all cathodes, a plurality of switching circuits one each connected 60 between the respective cathodes and said source, each circuit including a p-n-p transistor connected in emitter-follower configuration, means for connecting signal inputs to the base and emitter of each transistor respectively, means for biasing said transistors to operate in switching characteristic, and means for isolating said circuits from one another.

10. A structure as claimed in claim 9 in which said last mentioned means comprise series diodes in the cathode circuits and in the input signal connecting means.
